NORTH CAROLINA.

JACQUARD.

1,299,771.

Specification of Letters Patent.

Patented Apr. 8, 1919.

Application filed August 2, 1915. Serial No. 43,255.

To all whom it may concern:

Be it known that we, JOHN L. PATTERSON and LOUIS S. CANNON, citizens of the United States, residing, respectively, at Roanoke

5 Rapids and at Rosemary, both in the county of Halifax and State of North Carolina, have invented certain new and useful Improvements in Jacquards, of which the following is a specification.

10 This invention relates to jacquards for use with looms, and particularly to a modification of a portion of the jacquard mechanism to render it positive in its action and thus better suited to the control of pattern reverse 15 mechanisms, card repeaters, stop motions, counters, box-motions and the like.

The invention is applied to existing jacquards by substituting a special needle and a corresponding special upright for a regular 20 needle and upright, and adding an auxiliary blade to the griff frame. The special upright has its hook reversed so that it engages the auxiliary griff blade when the special needle is forced back. The special needle has an 25 enlarged head lying in a countersunk hole in the needle board and is forced back by projecting clips mounted on the ends of appropriate cards. These clips are engaged by the card cylinder when the card is presented, and 30 are forced into the countersunk hole. The reversal of the hook of the upright gives it a normal freedom from the griff blade making accidental actuation impossible, while the size and arrangement of the parts is 35 readily made such as to secure a far more certain action than can be had with the usual card and needle. An additional advantage is the ready identification of the control cards by the presence upon them of the clips. 40 This permits quick inspection in case of faulty action and is a convenience to the weaver.

One or more of the special needles and uprights may be used according to the requirements of the jacquard control mechanism, the special upright or uprights being connected in any approved manner to the reverser, card repeater or the like to actuate the latter.

45 The invention is generally applicable in lieu of the conventional jacquard needle and upright in the various mechanisms in which these are used to control the travel of the pattern series, etc. It may thus serve to 50 actuate the pattern reverse in simple revers-

ing jacquards; the card repeater in reversing jacquards having body repeat and border patterns in a single series (see patent to Patten No. 578,068); the card repeater in auxiliary cylinder jacquards (see patent to 60 Deering No. 953,879); and various other repeating and reversing mechanisms. It may also be used with conventional forms of stop motion to bring the loom to rest at stated points in the pattern. This is useful where 65 the filling is to be changed as in weaving color stripes in borders. It may also be used to actuate counters to indicate the number of complete patterns woven, and also to operate boxes on looms. 70

We show the invention as applied to an auxiliary cylinder jacquard to control the operation of the cylinders, in the accompanying drawings, in which:

Figure 1 is a side elevation of a jacquard, 75 various parts not necessary to an understanding of the invention being omitted;

Fig. 2 is a diagrammatic vertical section indicating the relation of the needles, hooks and the griff bar and showing the relation 80 of the needles to the two pattern cylinders;

Fig. 3 is a detail elevation of a form of card repeater or control mechanism known in the art and available for use with the invention; 85

Fig. 4 is a perspective view of one end of a card showing the clip attached;

Fig. 5 is a fragmentary horizontal section through the needle board showing the special needle mounted in a countersunk recess and 90 also showing the relation of this needle to the card and the clip carried thereby;

Fig. 6 is a fragmentary perspective view of a portion of one of the regular griff bars showing the special griff bar attached thereto and the relation of these parts to the special and regular uprights. 95

In the drawings 7 represents the frame of the jacquard, 8 is the main cylinder and 9 is the auxiliary cylinder. The main cylinder 100 coacts in the usual way with the needle board 10, having a bank of needles 11, which control the usual series of uprights 12, the parts being so arranged that when a needle is indicated by a hole in a pattern card the corresponding upright will be hooked to its griff bar; but when the needle is forced back by the card, the upright will be carried clear of the griff bar. The same uprights are also operated by means of a bank of auxiliary 105 110

needles 13 which pass through an auxiliary needle board 14, and with which the auxiliary cylinder 9 coacts. The auxiliary needles are connected to corresponding main 5 needles by means of rock levers 15, pivoted in the usual way as diagrammatically illustrated at 16. Thus the effect of any pattern series on the uprights would be the same whether presented by the main or the auxiliary cylinder. In the ordinary use of such a jacquard one cylinder carries the cross border pattern and the other carries the body pattern, either as a complete pattern, or as a repeating section.

15 The cylinders 8 and 9 are guided in their motions toward and from their respective needle boards by the guide rods 17 and 18 which may be alternately latched to a rocker arm 19 driven in any suitable manner. The 20 method of connection is through two slide bars 20 and 21 which run on the inner ends of the guides 17 and 18. These carry gravity pawls 22 and 23 which when lowered engage studs 24 and 25 on the slide bars 17 and 18 25 respectively. Only one of the pawls 22 and 23 is permitted to be in engagement at once, one or the other being held up by an S-shaped rocker arm 26 pivoted at 27 on the frame 7.

30 This rocker arm 26 is actuated through a link 28 from a lever 29 whose position is controlled by a pattern chain 30. This chain 30 runs on a sprocket 32 which is periodically fed forward one tooth at a time as will 35 be described. Certain of the links have enlargements or bosses 31. When an enlargement or boss 31 is under the lever 29 it raises this lever and shifts the arm 26 to disengage the pawl 23 and permit the pawl 22 to engage. When a link having no enlargement 31 is beneath the lever 29 this drops and the arm 26 shifts to change the action of the pawls. Thus the pattern chain determines which of the cylinders 8 and 9 is in operation 40 to control the uprights 12. A pawl 33 is actuated each pick by the movement of the lever 19 to which it is connected. The pawl is normally held up by a spring-held lever 34 which engages a lug 35 on the pawl 33. When the lever 34 is drawn down against its spring the pawl 33 may engage a ratchet 36 to feed it forward one tooth, thus advancing the pattern chain one link.

45 The mechanism so far described has been 50 used for controlling auxiliary cylinder jacquards, the operation of the lever 34 being effected by connecting it to an upright in the jacquard which is operated through the indication of its corresponding needle by a 55 corresponding hole presented in the terminal card of the series. False indication and failure to indicate are common occurrences in such devices, and cause serious losses of time and material. To avoid the uncertainty of jacquard indication we have de-

vised a new mechanism for controlling the above described device and other similar devices, our improved mechanism being readily applicable to existing jacquards.

The lever 34 is connected by means of cords 37 and a bell crank 38 to an upright 39. This upright is similar to the usual uprights used in the jacquard except that its hook at the upper end is turned in the reverse direction and may be engaged and 75 lifted by an auxiliary griff blade 40 mounted on one of the usual griff blades 41. The reversal of the hook on the upright 39 causes this upright always to remain in its lower position unless positively shifted to hook 80 upon the auxiliary blade 40. The special upright 39 is connected in the usual manner to special needles 42 in the main and auxiliary banks which have enlarged heads 43. These are shown in Fig. 5 as formed by 85 bending the end portion of the needles into loops. The enlarged heads 43 of the special needles 42 are countersunk into their respective needle boards 10 and 14.

The ordinary pattern needles remain unchanged and coact with the cards in the usual manner but the special needles 42 can only be actuated by a projecting clip 44 which is commonly made of metal and riveted to the end of the proper pattern card 90 45, as best shown in Figs. 4 and 5. Whenever a card carrying the clip 44 is presented in either pattern series the special upright 39 is shifted to engage the special griff blade 40 and consequently the lever 34 is momentarily drawn down through the connections 37 and 38 thus causing the pattern chain 30 to be fed forward one link and perform its usual function in controlling the alternate action of the two pattern series 8 and 9. 105

The fact that the special needle is countersunk precludes any accidental actuation due to misplaced or over-running cards in the series and the relatively large size of the parts insures peculiarly certain operation 110 whenever a clip card is presented. The presence of the clips on the cards allows the weaver to see how the pattern is progressing even at some distance from the loom, and in case of defective operation permits 115 ready identification of the control cards.

The invention is readily applied to existing looms by simply changing the needles, reversing the hook on the upright, and adding the special griff blade. It is not confined in its utility to auxiliary cylinder jacquards but as already suggested is generally applicable wherever card repeaters and analogous devices are used in this art. In some cases more than one special needle might be 120 used in a single bank of needles, for example in looms where a pattern is caused to reverse at its opposite ends, and the different reverse mechanisms are individually actuated. A single bank might also be provided 125 130

with more than one special needle, one for example controlling a card repeater and another a stop mechanism to mark the point where the filling is to be changed in color.

5 Various such uses will suggest themselves to those skilled in the art, and fall within the scope of our invention.

Various changes are possible in the construction of the cards, needles and similar

10 parts. One of the important advantages of the device arises from the fact that the special needle is beyond the range of action of ordinary cards, the special cards being provided with extensions to permit them to 15 coact with the special needle. The use of a countersunk needle and a projecting lug affords the most convenient means of avail- 20 ing of this principle, because it does not require a special location for the needle other than the countersinking of its end. Other 25 locations of the special needle are, however, possible for use with cards having suitable extensions or projections to coact therewith. The special griff blade and hook are also subject to possible modifications of form.

Having thus described our invention, what we claim is:—

1. The combination with a jacquard hav- 30 ing the usual griff mechanism, uprights, needles and pattern-card series, of a pattern- controlling mechanism; a pattern-control upright operatively connected with said controlling mechanism for controlling the operation of the latter, said pattern control up- 35 right being normally free of said griff mechanism; a pattern-control needle operatively connected with said pattern-control upright for moving the same into engagement with said griff mechanism; and means carried by 40 chosen cards of the pattern series for actuating said needle.

2. The combination with a jacquard hav- 45 ing the usual griff mechanism, uprights, needles and pattern-card series, of a pattern- controlling mechanism; a pattern-control upright operatively connected with said controlling mechanism for controlling the operation of the latter, said pattern-control up- 50 right being normally free of said griff mechanism; a pattern-control needle situated out of the range of action of ordinary pattern cards of the series and operatively connected with said pattern-control upright for moving the same into engagement with the griff 55 mechanism; and extensions carried by one or more cards of the pattern series for engaging and actuating said control needle.

3. The combination with a jacquard hav- 60 ing the usual griff mechanism, uprights, needles and pattern-card series, of a pattern- controlling mechanism; a pattern-control upright operatively connected with said controlling mechanism for controlling the operation of the latter, said pattern-control up- 65 right being normally free of said griff mech-

anism; a countersunk control-needle opera- 70 tively connected with said pattern-control upright for moving the same into engagement with the griff-mechanism; and projecting lugs carried by one or more cards of the pattern series for actuating said countersunk needle by the presentation of such cards to the regular needles of the jacquard.

4. The combination with a jacquard hav- 75 ing the usual griff mechanism, uprights, needles, pattern card series and card presenting mechanism, of a pattern chain mechanism operatively related to the card presenting mechanism for controlling the action of the latter; a control-upright operatively connected with said pattern chain mechanism for controlling the operation of the latter, said upright being normally free of said griff-mechanism; a pattern control needle situated out of the range of action of the 80 pattern cards and operatively connected with said pattern-control upright for moving the same into engagement with the griff mechanism; and means carried by one or more cards of the series for engaging and 85 actuating said control needle.

5. A device for actuating secondary mech- 90 anisms from a jacquard, comprising in com- bination with the jacquard, a control-needle; an upright normally out of engaging rela- 95 tion with the griff mechanism of the jac- quard and operatively connected with the control-needle to be moved into such relation by the actuation of the needle; and means carried by one or more of the jacquard cards 100 for actuating said control-needle.

6. A device for actuating secondary mech- 105 anisms from a jacquard, comprising in com- bination with the jacquard a control-needle beyond the range of action of the jacquard cards; an upright normally out of engaging rela- 110 tion with the griff mechanism of the jac- quard and operatively connected with the control needle to be moved into such relation by the actuation of the needle; and exten- 115 sions carried by one or more of the jacquard cards for actuating said control needle.

7. A device for actuating secondary mech- 120 anisms from a jacquard comprising in com- bination with the jacquard, a countersunk 115 needle; an upright normally out of engag- ing relation with the griff mechanism of the jacquard and operatively connected with said countersunk needle to be moved into such relation by the actuation of the needle; 120 and projections on one or more of the jac- quard cards for actuating said countersunk needle.

8. A device for actuating secondary mech- 125 anisms from a jacquard, comprising in com- bination with the jacquard, a countersunk 125 needle; an upright normally out of engag- ing relation with the griff mechanism of the jacquard and operatively connected with said countersunk needle to be moved into 130

such relation by the actuation of the needle; and metallic clips for actuating said countersunk needle, attached to chosen ones of the jacquard cards and projecting from the 5 faces thereof.

9. A device for actuating secondary mechanisms from a jacquard, comprising in combination with the jacquard, a control-needle; an upright normally out of engaging relation with the griff mechanism of the jacquard and operatively connected with the control-needle to be moved into such relation by the actuation of said needle; and a pattern-card series for the jacquard containing 10 one or more cards capable of actuating said needle.

10. The combination with a jacquard having a plurality of pattern needles, and a plurality of pattern uprights normally in 20 engagement with the griff mechanism of the jacquard and operatively connected with their respective needles to be moved out of such relation by the actuation of said needles, of a control upright adapted to be 25 connected to a secondary mechanism to control the operation of the latter, said upright being normally out of engaging relation with the griff mechanism of the jacquard; a control-needle operatively connected thereto to move said control upright into 30 engaging relation with the griff mechanism of the jacquard upon the actuation of said control-needle; and a pattern card series for the jacquard containing one or more cards 35 adapted to actuate said control-needle.

11. The combination with a jacquard including a plurality of pattern uprights normally in engagement with the griff mechanism of the jacquard, and a plurality of 40 pattern needles operatively connected to said uprights to move the same out of engagement with said griff mechanism when the respective needles are actuated, of a control upright adapted to be connected to a secondary 45 mechanism to control the operation of the latter, said control upright being normally out of engagement with the griff mechanism of the jacquard; a control needle operatively connected with the control upright to move the latter into engagement 50 with the griff mechanism of the jacquard and incapable of operation by an ordinary

jacquard card; a jacquard pattern-card series for operating said pattern needles; and extensions carried by one or more of the cards 55 of said series, adapted to actuate said control needle.

12. The combination with a jacquard including a griff mechanism, hooked pattern uprights, and pattern needles operatively 60 connected with said pattern uprights, of a control upright included in a row of pattern uprights and having a hook extending in the opposite direction from the hooks of said pattern uprights; a needle associated with 65 the pattern needles and operatively connected to said control upright to actuate the latter; and an auxiliary griff blade operatively connected to said griff mechanism and adapted to coact with the hook of said control upright. 70

13. The combination with a jacquard including a griff mechanism, hooked pattern uprights, and pattern needles operatively connected with said pattern uprights, of a 75 control upright included in a row of pattern uprights and having a hook extending in the opposite direction from the hooks of said pattern uprights; a needle board for said pattern needles; a control needle operatively connected to said control upright and having its end located in a countersink in said needle board; a card presenting mechanism; a pattern card series adapted to be presented to the needle board thereby; and 80 projecting lugs carried by one or more of said cards for actuating said control needle. 85

14. In a jacquard the combination of a griff mechanism, a plurality of pattern uprights having hooks adapted normally to be 90 engaged by said griff mechanism; pattern needles operatively connected with said uprights; a control upright having a hook reversed in direction with respect to the hooks of the pattern uprights and mounted in a 95 row with the pattern uprights; an auxiliary griff blade for said control hook carried by said griff mechanism; and a control needle associated with said pattern needles and operatively connected to said control hook. 100

In testimony whereof we have signed our names to this specification.

JOHN L. PATTERSON.
LOUIS S. CANNON.
